1

This invention relates to warping machines, such as warping machines for winding warp beams for use in warp knitting machines.

In winding warp beams, the warps pass from the creel over tension rollers and then through a reed, and are then wound on a beam or bobbin mounted horizontally between spindles through which the beam is driven. As the process continues, the diameter of the warp on the beam increases, so that the direction of the threads as they pass through the reed changes, unless the height of the winding spindles is altered progressively during the process. Also, if the speed of the spindles is kept constant, the winding rate will progressively increase, and it is, therefore, desirable that, throughout the process, the speed of rotation of the spindles should be progressively reduced if the beam is to be wound evenly and at constant tension. In winding beams of large diameter, the increase in diameter of the beam is so great that the operator finds great difficulty in watching the warp yarns throughout the process, unless some arrangement is made to keep their height as they pass through the reed substantially constant. In addition, the weight of thread wound on to a beam of, say, thirty-six inches diameter when fully wound, is such that the braking effort necessary to arrest the beam rapidly when fully wound is so much greater than that required to produce a similar action at the beginning of winding, that it is necessary to provide an arrangement for varying the braking effort as the diameter of the beam increases.

The present invention provides an improved warping machine having an arrangement to ensure a constant warp speed, and adapted to handle beams of very large diameter when fully wound. The operation of setting the beam in the machine and removing it when wound is made simple and easy and the machine automatically adjusts the height of the beam during winding so that the path of the warp threads through the reed remains substantially constant, while the mechanism for applying braking to the beam is varied so that the braking effort is kept consonant with the inertia of the mass of warp on the beam at any moment. Furthermore, the tension rollers are provided with arrangements so that they are also braked when the machine is stopped and, in addition, may be adjustably braked during the running of the machine in a way which allows the yarn to be drawn off the creel under minimum tension, but permits the desired amount of tension to be applied to the yarn before it reaches the reed of the beam. The

2

tension rollers are arranged so as to permit very easy and simple threading of this part of the mechanism. The machine is also equipped with safety devices which include a beam guard rail, which can be turned out of the way for loading or manipulating the beam or the yarns, in which position it is impossible to start the machine.

According to the present invention, the beam is mounted horizontally between spindles, one at least of which is power-driven, which are carried by arms which can be raised and lowered by power-driven means permitting the arms to be lowered so that the beam may be set in the machine at floor height and then raised to the correct height for winding. Provision is made for the control of the means for raising the arms then to be transferred to a finger or feeler which rests lightly on the upper surface of part of the warp threads, close to where they pass through the reed, and, as the diameter of the beam increases during winding, the increasing height of these yarns causes them to raise the finger which acts through suitable relays to lower the beam supporting arms till the yarns are once more at their correct height.

The arms carry braking mechanism for stopping the beam spindles and the raising and lowering of the arms causes a follower to move over a cam surface to vary the braking effort applicable to the spindles according to the diameter of the warp on the beam. To this end, a brake may be operated by the release of an arm loaded by a spring the stress in which is varied by a cam fixed to the machine frame and engaged by a follower connected to the spring and carried by the beam supporting arms, as these arms are raised and lowered. The yarn tension rollers drive a brake drum to which a brake is applied when the machine is stopped, and this drum may be associated with a further brake drum to which an adjustable constant braking effort is applied to impart tension to the warp.

A speedometer mechanism is driven by a roller caused to rotate by the passage of the warp yarns from the creel to the beams, so that its speed is proportional to the speed of the warp yarns. The speedometer pointer moves over a dial which is provided with a hand-set pointer, which may be set by the operator to the maximum speed at which it is desired the yarn should travel. The two pointers are provided with contacts which are closed when the speedometer pointer reaches the hand-set pointer completing a circuit which acts to reduce the speed of the main driving motor for the beam, so that each time the yarn

speed reaches the maximum desirable, the motor speed is reduced slightly with the result that the yarn speed remains substantially constant.

An example of a warping machine according to the invention is illustrated in the accompanying drawings in which:

Figure 1 is a side elevation of the complete machine;

Figures 2 and 2A are a rear elevation as seen from the left-hand in Figure 1;

Figures 3 and 3A are a front elevation as seen from the right-hand in Figure 1;

Figures 4 and 4A are a plan view of the machine shown in Figure 1;

Figure 5 is a detail view in part section of the left-hand beam spindle as seen in Figures 3 and 4;

Figure 6 is a detail of the screw jacks;

Figure 7 is a detail of the arrangement for providing variable braking effort;

Figures 8 and 9 show details of the yarn tensioning arrangement;

Figure 10 shows the warp tensioning arrangement and the beam level control;

Figure 11 is a detail of the yardage counter and beam level control;

Figure 12 is a side view of the arrangement for measuring and controlling warp speed;

Figure 13 is a view of the apparatus shown in Figure 12 as seen from the right in that figure;

Figure 14 is a view of the dial of the apparatus shown in Figures 12 and 13;

Figure 15 is a detail showing the hub of the right-hand arm, as seen in Figures 3 and 4, illustrating the arrangement for limiting the movement of the arms;

Figure 16 is a detail showing the guard rail and hand control arrangements;

Figure 17 is a side elevation of the right-hand part of Figure 16; and

Figure 18 is a diagram showing the electrical circuits.

Referring to Figures 1 to 4, the beam 1 is carried between spindles 2 and 3, journaled at the ends of a pair of tubular arms 4 and 5 having hubs 7 and 8 respectively which are pivotally mounted on the base 6 of the machine. The arms 4 and 5 have housings 9 for trunnions which are engaged by the screw jacks 10 which are driven by gearing in the feet 11 so as to raise and lower the arms.

The beam 1 is driven by a belt drive 12 in a guard 13 from pulleys 14 on a shaft passing through the hub 7 of the arm 4 and driven by the main variable speed motor 15 through a main clutch 16 operated by a solenoid 16A and a gear box 17.

The warp threads are drawn from a conventional creel, as at 18 in Figure 1, between guide bars 19, 20, through the teeth of a comb or sley bar 25, over a tension roller 21, beneath a tension roller 22, and over a tension roller 23. The drive to the yarn speed indicator and controller 24 is taken from the roller 21. The yarns then pass through the droppers 25A of a conventional stop motion (see Figures 10 and 18) and a deflector rod 164, whereafter the yarns 26 pass through a second comb or sley bar 27, which is adjustable in the direction of the warp threads and also laterally by a micrometer adjustment 27A, and then to the beam 1. As seen in Figures 1, 4 and 4A, the warp height detector 28 and yardage counter 29 are mounted on a pillar 30 carried by one of a pair of forwardly projecting brackets 31 and 32 which are mounted above

the motor housing 33 and also serve to support the sley bar 27.

As seen in Figure 5, the arm 4 carries a cylindrical housing 34 in which a sleeve 35, to which is connected a splined ring 40, is supported in ball-bearings 36 and roller-bearings 37. This sleeve carries a brake drum 38 to the rim of which a double V pulley 39 is secured for the belt drive 12. The ring 40 is splined internally to engage corresponding splines 41 on the spindle 2 which passes through the centre of the sleeve 35, thus being driven by the splines although free to move axially. The outer end of the spindle 2 is threaded at 42 and is engaged by an internally threaded hand-wheel 43, the thrust of the spindle being transmitted to the hand-wheel and thence by a ring 44 to a retaining ring 45 secured to the brake drum 38. By turning the handwheel, the spindle 2 may be adjusted axially while the pulley 39 is stationary. The inner end of the spindle 2 is provided with a spigot 46 to centre the beam 1 and a flange 47 to provide a locating face for the end of the beam. A driving dog 48 is provided on the face of the flange 47, so that the beam 1 is positively driven. The arrangement of the bearings and adjustment for the spindle 3 of the arm 5 are similar to those shown in Figure 5, except that the driving pulley 39 is omitted.

As seen in Figure 6, the jack 10 for the arm 4 works in the threaded trunnion block 49, mounted in bearings 50 in a cylindrical housing 9 about two thirds of the way along the arm 4. The lower end of the jack 10 is supported by a roller thrust bearing 52, so that the weight of the beam 1 and arm 4 is transmitted through this bearing to the strong toe 11. The jack is driven from a bevel gear 53 keyed to the lower end of the jack 10 and meshing with a bevel gear 54 keyed to a horizontal transverse shaft 55 which carries a spur wheel 56. This spur wheel is driven, as seen in Figure 1, through a reduction gear train 57, 58 from a pinion 59 on the armature shaft of an electric motor 60 (see Figure 3). The jack 10 for the arm 5 is supported in a similar way and driven by similar bevel gears from a shaft 61 which is driven from the shaft 55 by a torque tube 62 (see Figures 3 and 6). The motor 60 is reversible so that the arms 4 and 5 with their loads can be raised and lowered.

The brakes for each of the spindles 2 and 3 are of the internally expanding Girling type operated by the mechanism shown in Figure 4 and Figure 7, which latter figure shows a side view of the linkage for the brake of the spindle 2. The brake is applied by withdrawing the plunger 63 from the brake mechanism housed within the brake drum 38. The plunger 63 is pivoted to the bell-crank 64, secured to a shaft 65, and having its other arm pivotally connected by a link 66 to a rocker 67 which is pivotally supported at 68 by a spring loaded plunger 69 sliding in a cylinder 70, which is carried by a bracket 71 projecting from the hub 7 of the arm 4 in the opposite direction to the arm 4. The bracket 71 is provided with a number of holes 72 for a fulcrum pin 73 against which the rocker 67 is pressed by the action of the spring 74, the other end of which bears against a plunger 75 which rides on a cam face 76 fastened to the framework of the machine. Thus, as the arms are raised and lowered, the plunger 75 moves over the cam face 76 causing the compression of the spring 74 to vary with consequent varia-

tion of the effort which may be applied to the brake 38. The holes 72 enable the mechanical advantage of the spring 74 to be altered. The brake is normally held in the off condition by an arm 77 secured to the lower end of the shaft 65. This arm is prevented from turning to allow the brake to be applied, by the short trigger arm 78 of a bell-crank pivoted on a shaft 79 and having a long arm linked by a link 80 to the armature 81 of a solenoid 82. So long as the solenoid 82 is energised, the arm 78 engages the arm 77 as seen in Figure 3, holding the brake off, but, if the current to the solenoid 82 is interrupted, the armature 81 drops so that the arm 78 is turned out of the path of the arm 77, with the result that the force of the spring 74 is permitted to act to apply the brake. A light spring 83 is also fitted between the bell-crank 64 and a bracket 85 anchored to the solenoid 82.

The levelling and tensioning rollers 21, 22, 23 are arranged as shown in Figures 2, 4 and 10, and the centre roller 22 is pivoted between the ends of a pair of arms 84 which are pivoted at 85 so that the roller 22 can be swung clear of the warp threads into the position shown dotted in Figure 1. This makes for easy threading up. The roller 22 can be set in its working position at five different heights, enabling the warp tension to be determined very accurately, by a spring loaded plunger 84A engageable with any one of five holes 84B (Figure 12). The rollers are provided with belt pulleys 86 at one end so that their rotation drives a belt 87 (see Figures 2 and 10) which also passes round a pulley 88 on a brake shaft 89. A pair of jockey pulleys 90 are mounted on a plate 91 so as to lie one on either side of the belt 87. The plate 91 is pivoted at 92 so that these jockey pulleys may be turned to adjust the tension in the belt 87 and locked in position by the nut 93. The shaft 89 carries a pair of brake drums 94, 95 as shown in Figures 8 and 9. The brake drum 95 is continuously engaged by a brake shoe 96 mounted to rock on a lever arm 97 by the pivot 98. The arm 97 is pivoted at 99 and is engaged at its other end by one end of a compression spring 100, the pressure of which is adjustable by the threaded abutment sleeve 101 against which the other end of the spring 100 presses. Thus, by turning the knob 102 on the sleeve 101, the retarding force on the brake drum 95 is varied, consequently varying the tension in the warp threads. To bring the rollers 21, 22, 23 to a standstill, when the machine is stopped, brake shoes 103, 104 are biased by a spring (not shown) to engage the brake drum 94, and are normally held out of engagement by a solenoid 105 which urges the brake shoes 103, 104 apart by means of the rod 106.

As seen in Figures 2, 4, 12 and 13, the roller 21 is also provided with a pulley 107 from which a pulley 108 is driven by a belt 109. The pulley 108 drives a speedometer 24 through gearing housed in the case 110. The dial 111 of this instrument is illustrated in Figure 14 and is graduated suitably in, for instance, yards per minute. The speedometer pointer 112 moves over this scale, and a second pointer 113 is provided which can be set by hand by means of the knob 114 which has an arm 114A which can then be locked in place by a padlock 115, the hasp of which passes through a hole 116 in the end of the arm 114 and one of a corresponding series of holes 117 in a flange 118 surrounding the dial of the instrument. The pointers 112, 113

and 113 are electrically insulated from each other but are provided with contacts 119, 120 respectively, which make when the pointer 112 reaches coincidence with the pointer 113, closing 5 a circuit which acts to reduce the speed of the main driving motor 15 (see Figure 2). The speed of this motor 15 is controlled by rocking the brush gear by means of a small motor 121 provided with a change-speed gear box 122 from which conventional brush rocking mechanism is driven by means of a chain 123 seen in Figures 2 and 3. The contact 119, 120 controls the motor 121 to run in either direction by means of relays 121A, 121B housed in a relay and switch box 124 which contains all the electrical controls.

The gear box 122 has two alternative gear ratios, the slower of which gear is used when running normally, and the faster of which is engaged by a clutch operated by a solenoid 122A 20 when the speed of the machine is controlled by the operator.

As seen best in Figures 1, 4 and 11, the yardage counter 29 is driven by a multiple V pulley 125 round which a number of warp threads are taken, so that as the warp runs from the creel to the beam 1, a suitably arranged revolution counter is driven. The yardage counter 29 is mounted on a bracket 126 which also carries the beam height control 28 and may be clamped in any 30 desired position on the pillar 30 by the clamping screw 127.

The beam height control 28 has a light feeler 128 which rests across a number of the warp threads 26 which do not pass round the pulley 125. The feeler is carried by a pivot disc 129 which also has a balance arm 130 with an adjustable counter-balance 131, and an L-shaped arm 132 having an insulated tip 133 arranged to bear upon the back of a flexible blade 134 carrying a contact 135. A fixed contact with the contact 136, is adjusted so that it is normally not in contact with the contact 135, but when the height of the warp yarns rises sufficiently the arm 132 presses the contact 135 against the contact 136, closing a circuit through the leads 137, 138, to excite a control circuit 138A in the case 124 with the result that the motor 60 for the jacks 10 is driven so that the beam 1 is lowered slightly. In this way, the beam 1 is lowered progressively as its diameter increases, as shown in Figure 10, thus maintaining the path of the warp through the machine substantially constant.

To prevent damage which might result from driving the jacks 10 too far in either direction, raising the arms too high or lowering them below the height at which the beam rests on the floor, a pair of adjustable screw stops 139, 140 are mounted on the pivot hub 8 of the arm 5 in a housing 141 (see Figures 3, 4 and 15). The housing 141 is mounted on the frame of the machine 60 by bolts 142 and carries a pair of micro-switches 143, 144. The stops 139, 140 are arranged and adjusted so that the stop 139 operates the micro-switch 143 when the arms are at the lowest desirable position and the stop 140 operates the micro-switch 144 when the arms 4 and 5 reach their highest desirable position. The micro-switches 143, 144 act through relays 138A, 144A and switches 138B, 144B in the case 124 to switch off the jack motor 60, as shown in Figure 18.

As seen in Figures 16 and 17, a guard rail 145 is provided, supported by bracket arms 146, 147 pivoted to brackets 148, 149 carried at the extreme ends of the arms 4 and 5 respectively, so 70 as to turn about the pivot pins 150, to prevent

the operator approaching the beam while the machine is working. This guard rail 145 is arranged to slide axially in the brackets 146, 147, being held normally in a mid position by a pair of springs 151 acting on opposite sides of a collar 152 secured to the guard rail 145. These springs and this collar 152 are housed in the bracket 146 which also forms a convenient platform for a control panel 153. The starting and stopping of the main driving motor 15 is controlled by 10 axial movement of the guard rail 145 by means of a pair of switches 154, 155 respectively. A cam member 156 is provided, on the guard rail 145 within the bracket 147, against which a pair of push rods 157, 158 are pressed by means of 15 springs 159 (see Figure 17). In the position shown in Figure 16, these rods bear on the switches 154, 155 so that neither switch is closed, but if the rod 145 is moved axially to the left, the push rod 157 is moved against its spring 159 and causes the switch 154 to close, energizing a 20 circuit 154A which acts to stop the whole machine. Movement of the guard rail 145 to the right as seen in Figure 16, causes the push rod 158 to close the switch 155, energizing a circuit 155A to start the main driving motor 15. The push rods 157, 158 are carried in brackets 160 secured to the arm 147. The switches 154, 155 are carried by a bracket 161 secured to the bracket 149. Thus, when the bracket arm 147 is raised from the position shown in Figure 17, to the position shown dotted in Figure 1 so that the guard rail 145 is carried clear of the beam, enabling the operator to reach the beam, the push rods 157, 158 are carried clear of the switches 154, 155 so that the mechanism cannot be started accidentally.

The jacks 10 may be adjusted by hand, by removing the cover 163 shown in Figures 3 and 4, enabling a detachable handle to be engaged with the exposed end of the shaft corresponding to the shaft 55.

A taping or gumming bar 162 is carried by the brackets 31, 32 and can be adjusted to suit the diameter of the warp on the beam when winding is completed. It enables gummed paper to be attached to the end of the warp easily and evenly and so that the warp ends are kept well separated. A static eliminator 165 is shown in Fig. 4A and is connected to associated circuits housed in the box 166.

A deflector rod 167 mounted close to the comb or sley bar 21, prevents the warp threads rising out of the sley bar 21 if the height control fails.

Push button controls 168, 169, 170 and 171 (see Figures 16 and 18) afford manual means for operating the brush rocking motor 121 for controlling the speed of the beam, and the reversible jack motor 60 for raising and lowering the beam, respectively.

We claim:

1. A warping machine comprising aligned spindles to support a warp beam, a guide fixed in position along side of and across the space between said spindles, power driven means to drive at least one of said spindles to cause said beam to draw warp threads past said guide onto said beam, movable arms supporting said spindles, power driven means to raise and lower said arms, a feeler engageable with at least some of said warp threads movably supported at a point between said guide and said beam, and means actuated by said feeler to control said means to raise and lower said arms.

2. A warping machine according to claim 1, in which the feeler is arranged to rest lightly on

5 the upper surface of some of the warp threads and, when the warp threads reach a predetermined height, acts to energize a circuit which controls the said power driven means so as to lower the arms.

3. A warping machine according to claim 1 in which said power driven means by which the arms are raised and lowered comprises screw jacks.

4. A warping machine according to claim 1, in which said power driven means is such that said arms can be lowered to a level at which said beam may be inserted and removed at the base level of the machine.

5. A warping machine according to claim 1, further comprising means to apply braking to at least one of said spindles and means to vary said braking comprising a cam and a follower connected to said braking means and caused to move over said cam by the raising and lowering of said arms.

6. A warping machine according to claim 5, in which the said braking means comprises brake shoes and the braking effort is applied to the brake shoes through a linkage by a stressed spring, and the follower is connected to the opposite end of the spring to that which is linked to the brake shoes.

7. A warping machine according to claim 6, in which the said cam is fixed to the framework of the machine and the follower projects from one end of a cylindrical housing for the spring, carried on the beam supporting arms, and a trigger is held in engagement with an arm connected to the brake operating linkage by a solenoid which is energized when the machine is running but which releases the said arm to permit said spring to exert a braking effort when the machine is being stopped.

8. A warping machine according to claim 1, further comprising tension rollers, a brake drum driven by said tension rollers and means to exert a variable retarding force on said brake drum.

9. A warping machine according to claim 8, further comprising a second brake drum driven by said tension rollers and means to exert a braking force on said second brake drum when the machine is to be stopped.

10. A warping machine according to claim 1, in which the second brake drum is driven from the tension rollers by a belt drive which is of variable tension.

11. A warping machine according to claim 1 further comprising tension rollers, a brake drum driven by said tension rollers, and means to exert a variable retarding force on said brake drum in which the brake drum is driven from the tension rollers by a belt drive which is of variable tension.

12. A warping machine according to claim 1 further comprising a series of tension rollers, a brake drum driven by said tension rollers, and means to exert a variable retarding force on said brake drum, in which the warp threads pass over a first tension roller, under a second tension roller and over a third tension roller, and the second tension roller is mounted between arms pivoted so that the second tension roller may be swung clear of the warp threads.

13. A warping machine according to claim 1, further comprising a speedometer movement, means to drive said speedometer movement at a speed proportional to the speed of said warp threads, a pointer actuated by said speedometer movement, a manually set pointer, a dial over

which said pointers move, contacts arranged to close when said speedometer pointer reaches said manually set pointer, and means energized by the closing of said contacts to reduce the speed of said spindle driving means.

14. A warping machine according to claim 13, further comprising means to set and lock said hand set pointer in any of a number of positions.

15. A warping machine according to claim 13, further comprising tension rollers and means to drive said speedometer movement from one of said tension rollers.

16. A warping machine according to claim 1, further comprising switches connected to stop said means to raise and lower said arms and means operated by the movement of said arms to actuate said switches when the arms reach the highest point desirable and when the arms reach the lowest point desirable.

17. A warping machine according to claim 16, in which the switches are micro-switches operated by adjustable stops carried on the hub of one of the arms.

18. A warping machine according to claim 1, further comprising a guard rail extending the length of said beam and carried by bracket arms pivoted to the extremities of said beam supporting arms, said guard rail having a safe and an unsafe position, a switch for starting the driving means for said spindles, and operating means for said switch connected to said guard rail and operable only when said rail is in the safe position.

19. A warping machine according to claim 18,

in which the switch is operated by an axial movement of the rail.

5 20. A warping machine according to claim 19, in which a second switch is provided operated by an axial movement of the rail in the opposite direction to stop the said driving means.

21. A warping machine according to claim 20, in which the rail carries a cam member having a cam-face which engages a spring-urged push rod to operate the starting switch when the rail is moved axially in one direction, and a second cam-face which engages a second spring-urged push rod to operate the stopping switch when the rail is moved in the opposite direction, and the push rods are carried by the bracket arms so that they do not engage the switches when the guard rail is swung out of the safe position.
